UNITED STATES PATENT OFFICE.

ELI R. DEMING, OF ALAMEDA, CALIFORNIA.

DESIGN FOR A SCRAPER.

No. 37,980.

Specification for Design.

Patented May 1, 1906.

Application filed August 15, 1905. Serial No. 274,344. Term of patent 7 years.

To all whom it may concern:

Be it known that I, ELI R. DEMING, a citizen of the United States, residing in Alameda, county of Alameda, State of California, have invented a new, original, and ornamental Design for Scrapers, reference being had to the accompanying drawing, in which the figure is a perspective of a scraper according to my new design.

I claim—

The ornamental design for a scraper as shown.

ELI R. DEMING.
